UNITED STATES PATENT OFFICE.

CHARLES F. PECKHAM, OF PROVIDENCE, RHODE ISLAND.

FUSIBLE LINK OR STRUT.

Application filed December 13, 1924. Serial No. 755,783.

My invention relates to fusible links, struts or similar connections employed with automatic fire-extinguishing systems for holding the valves of sprinkler-heads closed, or for retaining fire doors, shutters or the like normally open, and consists in improvements in the construction and method of operation of the same.

One object of the invention is to provide a device of the type specified in which the separable parts of the link or strut may be more securely bonded or held together by the fusible material, while being adapted for quicker release when exposed to a predetermined degree of heat.

Another object of the invention is to provide a link or strut in which the separable members interengage or interlock in such manner as to take the stress of the parts which they hold, without placing undue strain on the fusible material which bonds them together.

Another object of the invention is to provide a device of the type specified in which the separable parts of the links have a tendency to spring apart upon the fusing of their bond so that their release will be substantially instantaneous and positive without any chance of sticking or dragging.

Another object of the invention is to provide a link or strut of simple construction adapted for economical manufacture and capable of being produced in large quantities with greater uniformity to insure the required degree of accuracy in its control of the devices which it operates.

Further objects of the improvement are set forth in the following specification which describes a preferred embodiment of the invention as illustrated by the accompanying drawings. In the drawings:

Fig. 1 is a perspective view illustrating my improved fusible link or strut applied to use on a sprinkler-head to connect the arms or levers which hold the valve closed;

Fig. 2 is an enlarged plan view of the fusible link or strut showing it in its preferred form;

Fig. 3 is a greatly magnified plan view showing portions of the overlying strips of wire-netting or screen-cloth which form the two parts of the link with their strands interengaging to substantially lock the parts against longitudinal movement;

Fig. 4 is a lateral cross-sectional view taken on line 4-4 of Fig. 3, and also show-

ing the manner in which the strands of the two strips of screen-cloth interlock;

Fig. 5 is a similar magnified longitudinal sectional view taken on the line 5-5 of Fig. 3, and further illustrative of the interengagement of the strands of the two strips of screen-cloth; and

Fig. 6 is a plan view of a modified form of the improved fusible link or strut.

Referring first to Figs. 1 and 2 of the drawings, a preferred form of my improved link or strut comprises two sections or strips 2 and 3 of reticulated material, such as wire-netting or screen-cloth, laid one over the other and bonded together with solder or an equivalent fusible metal which is flowed through the interstices of the mesh.

To prevent the strands of the screen-cloth from pulling apart or ravelling at the ends of the strips 2 and 3 I may employ suitable binding-strips 4 of thin sheet-metal folded over the edges thereof and crimped thereagainst, or fastened permanently thereto with hard solder or by brazing. Each strip or section 2 and 3 of the link has a hole or eye 5 punched through the netting near its end, and preferably the eyes are formed partly in the binder-strips 4 after the latter are applied to the netting so that they serve as a reinforcement for the holes. As illustrated in Fig. 2, the holes or eyes 5 in the two strips 2 and 3 register where the ends of one strip overlie the punched portion of the other strip, it being noted that one strip preferably does not extend the full length of the other strip but is short of the edge of the binder-strip 4. It will be understood that the holes or eyes 5 provide means for engaging the link or strut with the hooked ends of the valve-levers 1 of the sprinkler-head H, see Fig. 1, or in other instances they may receive the hooks at the ends of the wire cords or chains employed for holding fire-doors or shutters. In either case the levers or other parts to be held together will engage against the reinforcing binder-strips 4 at the ends of the two members 2 and 3 so that there will be no tendency to pull apart the strands of the netting or screen-cloth.

Referring now to Figs. 3, 4 and 5, the two strips or sections 2 and 3 of the link are superimposed in such manner that the projecting bends or "knuckles" of the lateral strands of wire on the face of one strip will interlock with or engage against the corre-

sponding bends or projections on the opposing face of the other strip. Fig. 4 represents a section of the screen-cloth taken laterally of the two overlying strips 2 and 3 and illustrates the manner in which the bends or "knuckles" *k* on the upper strip 2 overlap the bent strands *k'* on the under strip 3; or in other words this view shows how the bends of the wire on the face of one strip project into the interstices of the mesh on the other strip with the strands interlocking laterally across the strips. Fig. 5 also illustrates the interengagement or interlocking of the lateral strands at *k*, *k'*, the purpose of this arrangement being to restrain the two strips from sliding longitudinally with respect to each other.

After the strips 2 and 3 have been laid one over the other with their strands of wire interposed and interlocked in the manner as above described, the solder *s* or other fusible metal or alloy is flowed over them to bond the strips together. Usually the solder *s* is applied to the strips or members 2 and 3 across their full width and throughout the greater portion of their length, but leaving a narrow space between the solder and the edges of the binder-strips 4. The solder flows freely through the mesh of the strips and effects a continuous and substantial bond between the two members or parts of the link so that the joint is practically proof against accidental rupture or disintegration.

In Fig. 6 I have illustrated another embodiment of the invention in which the binding-strips at the ends of the members 2 and 3 are dispensed with and eyelets 6 inserted through the screen-cloth to provide means for connecting the link to the parts which it holds. Various other modifications may be made in the method of constructing and reinforcing the parts of the link without departing from the spirit or scope of the invention. The method of operation of the device is as follows:

After the two parts of the link have been placed one over the other and bonded together in the manner as above explained the whole forms a relatively light-weight, yet strong and sturdy connecting device which may be used for various purposes as well known to those versed in the art. When employed as a link or strut for sprinkler-heads, as shown in Fig. 1, the ends of the valve-levers 1 are hooked through the holes 5 at the ends of the link to hold the valve closed, and the link will sustain a very considerable stress without danger of rupturing the soldered bond and pulling the two sections apart. The interlocking engagement between the lateral strands or cross-wires of the two strips of netting tends to resist longitudinal displacement between the parts while they are held together by the solder, and the solder itself forms a very

secure and substantial bond since it penetrates through the interstices of the mesh of both strips. When, however, the link is subjected to an abnormal degree of heat the solder will be fused and the tensile strain on the two parts of the link will pull them apart to release the valve of the sprinkler-head, or in other words to release the connections of the fire-door or shutter.

With the present improved link or strut the rupture of the bond and the separation of the parts is accelerated and rendered practically instantaneous due to a peculiar coaction of the novel form of interlocking means hereinbefore described. Immediately the solder begins to soften under the effect of the heat there will be tendency for the two parts of the link to spring apart, due to a cam-action between the interlocked cross-wires of the netting. That is to say, the tensile strain tending to pull the link-members lengthwise will have the effect of camming the interengaged cross-wires one on another to cause them to ride up over each other to force the two members apart to more quickly break the soldered bond. In other words, the rupture of the bond is rendered more prompt, without any tendency for the parts of the link to cling and drag on each other. My invention therefore provides a more efficient and dependable device for the purpose intended which is more quickly responsive to break the connection when the heat reaches a prescribed degree.

The improved link or strut is adapted for economical manufacture and may be produced in quantity with a high degree of uniformity as regards the breaking factor, whereby it is rendered more accurate and dependable in its control. At the same time the peculiar construction of the link provides for a secure bond between the parts without danger of accidental rupture either in use or under rough handling.

Without limiting myself to the precise details of construction and arrangement of the device as herein shown and described, I claim:

1. A fusible link or strut comprising reticulated metal strips held in overlying relation by a bond of fusible material such as solder.

2. A fusible link or strut comprising reticulated metal strips held in overlying relation by a bond of fusible material and provided with means for connecting it with the parts to be held.

3. A fusible link or strut comprising reticulated metal strips held in overlying relation by a bond of fusible material and provided with eyes at either end adapted to engage the connections of the parts to be held.

4. A fusible link or strut comprising strips of wire screen-cloth held in overlying relation by a bond of fusible material and

- provided with reinforcing elements permanently secured to their ends to prevent the wires of the screen-cloth from pulling apart.
5. A fusible link or strut comprising strips of wire screen-cloth held in overlying relation by a bond of fusible material and having reinforcing strips of sheet-metal folded over their edges and permanently secured thereto to prevent the strands of the screen-cloth from pulling apart.
6. A fusible link or strut comprising reticulated metal strips disposed in overlying relation with the mesh of one strip interlocking with that of the other strip and bonded together by fusible material such as solder.
7. A fusible link or strut comprising overlying strips of wire screen-cloth disposed with the laterally extending strands of one strip interengaging with the corresponding strands of the other strip and held together by a bond of fusible material such as solder.
8. In a device of the type specified, the combination of superimposed strips of wire screen-cloth arranged with the bends of the wire strands on one strip projecting into the interstices of the other strip to interlock the wires to resist longitudinal displacement of one strip on the other, and fusible material flowed through the mesh of the strips to bond them together.

In testimony whereof I affix my signature.

CHARLES F. PECKHAM.
